PUMP

Torbjörn Viktor Dillström, Stockholm, Sweden,
assignor to Handelsaktiebolaget Vidar, Stockholm, Sweden, a corporation of Sweden

Application August 10, 1938, Serial No. 224,211
In Sweden September 28, 1937

17 Claims. (Cl. 103—41)

The present invention relates to plunger pumps for supplying liquid and has particular reference to pumps of this kind for supplying liquid fuel under pressure for injection into the cylinders of internal combustion engines.

The requirements for fuel injection pumps are particularly severe. In order for such pumps to inject fuel in a manner providing satisfactory engine operation they must inject fuel under very high pressure, they must act with extreme accuracy and precision, they must be capable of adjustment to vary the quantity of fuel delivered per cycle of operation and they must, when supplying fuel to a multiple cylinder engine, be capable of delivering, as nearly as possible, precisely the same quantity of fuel to each outlet for any given setting of pump capacity.

In order to meet these extremely rigid requirements, the most satisfactory type of pump arrangement heretofore developed has been that in which a separate cylinder and plunger is provided for each injector or other device to which fuel must be supplied and because of the extreme accuracy with which such pumps must be manufactured and the pressures involved, such pumps have proved to be very expensive to manufacture and also difficult to maintain in proper adjustment over long periods of service so that appreciable variation is not developed, through wear or other causes, in the quantities of fuel delivered to different outlets leading for example to injectors in different cylinders of the same engine.

It is the general object of the present invention to improve upon prior forms of construction of plunger pumps and to provide novel plunger pump structure which will enable liquids such as fuel oil to be supplied to a plurality of points of consumption with great accuracy of control both as to the quantity delivered and the relation of the quantities delivered by the pump to different outlets, while at the same time accomplishing the desired results with pump structure very much more simple and inexpensive than structures heretofore representing the best available for accomplishing the desired purpose.

To this end the invention contemplates the provision of improved plunger pump structure so constructed that liquid is delivered to a plurality of outlets from a common pump chamber through the action of a single plunger.

The manner in which the above general object, and other and more specific objects of the invention to be hereinafter pointed out, are attained, will best be understood from a consideration of the ensuing portion of this specification, taken in

conjunction with the accompanying drawings, in which is described various forms of constructional examples of pump structure for carrying the invention into effect.

In the drawings, Fig. 1 is a transverse section of a pump embodying the invention, taken in part along the line 1—1 of Fig. 2 and in part along line 1—1 of Fig. 3;

Fig. 2 is a fragmentary section taken on the line 2—2 of Fig. 1;

Fig. 3 is a section taken on the line 3—3 of Fig. 1;

Fig. 4 is a section taken on the line 4—4 of Fig. 1;

Fig. 5 is a section taken on the line 5—5 of Fig. 4;

Fig. 6 is an enlarged view of part of the pump plunger and barrel shown in Fig. 1, certain passages being turned into the plane of the drawing for clarity of illustration;

Fig. 7 is a developed view of the plunger and barrel surface of the pump shown in Fig. 1 with the plunger adjusted for maximum delivery;

Fig. 8 is a series of diagrams illustrating various phases of operation during the delivery stroke of the type of pump shown in Fig. 1, only two outlets being shown in the diagrams, however, for the sake of simplicity;

Fig. 9 shows different phases of the delivery stroke of a different form of plunger applicable to use in a pump of the general kind shown in Fig. 1;

Fig. 10 illustrates a different arrangement of outlet openings in a pump of the general kind shown in Fig. 1;

Fig. 11 illustrates in developed form the control portion of the plunger surface shown in Fig. 7, but in partial load position of adjustment;

Fig. 12 is a view similar to Fig. 11 showing a different form of control surface on the pump plunger for effecting a different mode of timing of part load delivery with respect to the timing of the pump actuating mechanism;

Fig. 13 is a view similar to Fig. 12 showing still another form of pump control surface for effecting yet another mode of timing of part load delivery;

Fig. 14 is a diagram illustrating a preferred cycle of movement of the pump plunger, particularly with reference to the delivery stroke;

Fig. 15 is a view showing a form of cam profile for securing the kind of plunger operation shown in Fig. 14;

Fig. 16 is a fragmentary section showing a

form of overflow arrangement different from that of Fig. 1;

Fig. 17 is a view similar to Fig. 16 showing still another overflow arrangement;

5 Fig. 18 is a partial section showing a different form of pump plunger and barrel construction for use in a pump of the kind shown in Fig. 1;

Fig. 19 is a central longitudinal section of the pump barrel of Fig. 18, taken on the lines 19-19 10 of Figs. 18 and 20;

Fig. 20 is a top plan view taken on line 20-20 of Fig. 19;

Fig. 21 is a section taken on line 21-21 of Fig. 19;

15 Fig. 22 is a series of diagrams illustrating different phases of delivery stroke operation of the plunger of the type shown in Fig. 18, only two outlets again being shown in these diagrams for the sake of simplicity;

20 Fig. 23 is a developed view of part of the barrel and plunger surfaces of the pump shown in Fig. 18;

Fig. 24 is a fragmentary section similar to Fig. 1 showing a pump having the same type of plunger as shown in Fig. 18 combined with a different form of tappet construction;

Fig. 25 is a diagram similar to Fig. 8 showing another form of cylinder porting arrangement;

30 Fig. 26 is a diagram similar to Fig. 25 showing still another porting arrangement providing precompression of fuel before delivery;

Fig. 27 is a diagram similar to Fig. 26 showing an arrangement providing variable degrees of 35 precompression;

Fig. 28 is a diagram similar to Fig. 27 but showing a different variation of precompression with respect to load adjustment of the pump;

Fig. 29 is a diagram illustrating a different form of plunger porting construction;

40 Fig. 30 is a diagram illustrating the features of Fig. 25 applied to a different form of plunger;

Fig. 31 is a diagram illustrating still another plunger porting arrangement;

45 Fig. 32 is a diagram similar to Fig. 31 showing a different arrangement for part load control;

50 Figs. 33 and 34 are diagrammatic sectional and developed views of still another arrangement providing for precompression with a plunger of the general type shown in Fig. 30; and

55 Figs. 35 and 36 are diagrammatic sectional and developed views respectively showing an arrangement providing for variable precompression with a plunger of the type shown in Fig. 33.

Referring now more particularly to Figs. 1 to 5, the pump illustrated is a single cylinder pump adapted to supply liquid fuel to four separate places of consumption such as fuel injectors. The pump comprises a casing part 10 in the base portion of which there is mounted a cam shaft 12 adapted to be driven from any suitable source of power and carrying cam 14 which may be integral with or fixed to the shaft. At the top 60 of the casing part 10 there is secured a head part 16, which is advantageously removably fixed to part 10 by a number of bolts, one of which is shown at 18.

The pump cylinder or barrel 20 is, in the embodiment illustrated, detachably secured to the head 16 by means of a threaded clamping collar 22 and is prevented from rotating with respect to the pump body by means of a locating pin 24. The pump plunger 26 is reciprocably mounted in the bore of barrel 20 and head 16 is bored 75 out in alignment with the bore of the barrel to

provide a pump chamber 28 with which the suction or supply conduit 30 communicates. Between the conduit 30 and the chamber 28 there is located the non-return suction valve which in the form shown is a spring loaded ball valve 5 32. It is to be noted in this connection that the flow of liquid to the pump chamber from the suction line is through a straight channel substantially unobstructed except for the suction valve. This is of importance as will be explained 10 later.

The pump barrel is provided with a series of longitudinally spaced relief or overflow ports r_1 , r_2 , r_3 and r_4 which as will be noted from Figs. 1 and 5 lie in alignment in a plane passing 15 through the axis of the pump barrel. These ports are connected respectively by branch overflow passages 34a, 34b, 34c and 34d to a common overflow passage 34 formed partially in the barrel and partially in the head part of the pump 20 casing.

The pump barrel is further provided with four outlet or delivery ports located in a zone above the overflow ports and advantageously distributed so as to open into the bore of the barrel in 25 different axial planes passing through the axis of the bore. These delivery ports, like the relief ports, are distributed in longitudinally spaced relation along the pump barrel. One of these ports d_1 is shown in Fig. 1 and the remaining 30 three ports, d_2 , d_3 , d_4 , appear in Fig. 5.

The ports d_1 to d_4 are connected respectively by delivery passages 36, 38, 40 and 42 to individual delivery conduits 36a, 38a, 40a and 42a. Each of the several delivery passages is provided with 35 a spring loaded discharge valve, the one controlling passage 36 being indicated at 44 in Fig. 1.

In the embodiment illustrated the several delivery ports are displaced peripherally with respect to adjacent ports by 90° and the line of 40 relief ports is also displaced peripherally with respect to two peripherally adjacent delivery ports (see Fig. 3). As will hereinafter more fully appear, the arrangement of the outlet ports peripherally of the barrel may be varied without 45 affecting pump operation.

The pump plunger is provided with two longitudinally separated recesses 46 and 48, both of which are in constant communication with the pump chamber 28 by means of a central longitudinal bore 50 in the pump plunger, which at one end opens into the pump chamber and which is placed in communication with the surfaces of the recesses by one or several transverse bores 52 and 54 respectively. 55

In the embodiment illustrated, the recess 46 encircles the periphery of the pump plunger while the recess 48 is provided with a special configuration to be described later.

Between the plunger and the cam there is provided a tappet 56 mounted for reciprocation in a suitable bore in the casing part 10 and at its lower end provided with a roller 58 contacting the face of the cam. The tappet is restrained against turning movement in the casing by 60 means of a locating pin 60 the inner end of which engages a suitable vertical slot 62 in the tappet. The upper portion of the tappet is of cup-like form providing a cylindrical recess into which the lower end of the pump plunger extends and against the bottom of which recess the enlarged foot 26a of the plunger rests. The foot 26a advantageously is formed with a convexly curved bottom surface as shown in Fig. 1. The bore of the tappet is shouldered to provide 70

a seat for a retaining washer 64 through which the plunger passes and which engages the upper surface of the foot 26a to prevent axial displacement of the plunger with respect to the tappet.

5 The retainer 64 is held in place by the pump plunger spring 66 which is compressed between this retainer and the collar 22. As will be evident from Fig. 1, spring 66 operates to cause the tappet and the pump plunger to follow the path 10 of travel determined by the profile of cam 14.

Adjustment of the quantity of fuel discharged by the pump is effected by turning the pump plunger about its axis and in order to effect this control, a segment 68 is provided having teeth 15 engaging the rack 70 slidably mounted for movement axially of itself in the pump casing. Rack 70 projects from the pump casing for connection to any suitable control for manual or automatic adjustment of the delivery capacity of the pump.

20 Turning movement imparted to segment 68 by movement of rack 70 is transmitted to the pump plunger by means of a pin 72 fixed at one end in the plunger and at its other end sliding in a vertical slot 74 in the segment 68. Pin 72 passes 25 through an arcuate slot 76 in the wall of the tappet, which permits the pin to be turned by rack 70 while the tappet remains rotationally stationary.

Referring now more particularly to Figs. 6 and 30 7, in which the pump cylinder and plunger arrangement shown in Fig. 1 has been shown on enlarged scale and in developed form for clarity, the plunger 26 has been shown in its position of rotational adjustment for full load operation.

35 Recess 46, which may conveniently be considered as the delivery recess, also constitutes a port in the plunger, defined by edges 46a and 46b, which port is conveniently designated as a plunger delivery port to distinguish it from the 40 delivery ports d_1 — d_4 , which are conveniently designated as cylinder delivery ports.

45 Recess 48, which may conveniently be considered as the overflow recess, has upper and lower limiting edges 48a and 48e and between and spaced from these edges there is provided a control portion 48' in the form of an island-like projection which extends partially around the circumference of the plunger and the surface of which is in contact with the wall of the cylinder bore. The control portion 48' provides two parallel transverse control edges 48b and 48d which operate, as will hereinafter more fully appear, to control the beginning and ending of full load delivery periods, and a third inclined edge 50 55 48c which in the embodiment illustrated merges at one end with edge 48b and operates to control the beginning of the delivery periods during part load operation. By reference to Fig. 7 it will be seen that the space between edge 48a on the one hand and edges 48b and 48c on the other hand provides a channel 48f in constant communication with the pump chamber, which channel constitutes an overflow port in the plunger which is conveniently designated as a plunger 60 65 overflow port to distinguish it from the cylinder overflow ports r_1 — r_4 . Likewise, a channel 48g, constituting a second plunger overflow port longitudinally spaced from the one formed by channel 48f and also in constant communication with the pump chamber, is formed by the space between edges 48d and 48e.

70 Referring now more particularly to Fig. 8, which shows the plunger in various positions on its delivery stroke and in which for the sake 75 of convenience only two relief or overflow ports

r_1 and r_2 , and two delivery ports d_1 and d_2 , have been shown, it is assumed that the pump chamber 28 is filled with liquid drawn thereinto from the suction conduit 30 by the preceding suction stroke of the plunger.

7 In position 8a, the plunger is assumed to be at the bottom of its stroke and about to ascend on its delivery stroke. In this position, the recess 46 is not in communication with any delivery port while the channel 48f, forming a part of the recess 48, is in communication with the relief port r_1 so that movement of the plunger on its delivery stroke is permitted by overflow of liquid from the pump chamber through the bores 50 and 54 in the plunger and through the overflow recess 48. 10 15

In position 8b, the plunger has moved upwardly until the upper control edge of the delivery recess 46 is just passing the lower edge of the delivery port d_1 , to place port d_1 in communication with the pump chamber by way of bores 50 and 52 in the plunger and the delivery recess. At the time the plunger reaches this position, channel 48f is still in communication with relief port r_1 so that when edge 46a passes the lower edge of port d_1 to establish delivery communication, delivery does not then take place because of the open overflow connection through the relief port. 20 25 30

When the plunger reaches the position 8c, the delivery port d_1 has been substantially opened and when the plunger reaches this position, delivery commences due to the channel 48f having passed out of communication with the relief port r_1 . This determines the instant of commencement of delivery and with the plunger in the full load position of rotation shown, which corresponds to the position shown in Fig. 7, it will be evident that commencement of injection is determined by the control edge 48b. 35 40 45

Continued movement of the plunger from the position shown at 8c to the position shown at 8d effects delivery through port d_1 which, it will be noted, is in communication with the delivery recess 46 during this period of movement of the plunger. When the plunger reaches the position 8d, the overflow channel 48g comes into communication with the relief port r_1 to terminate the delivery period and again by reference to Fig. 7 it will be evident that the end of the 50 delivery period will be determined by the control edge 48d. Thus the delivery through the port d_1 , which may be termed delivery period No. 1, occurs during movement of the plunger from position 8c to position 8d. Also, it will be noted 55 that the delivery recess 46 is in communication with the delivery port d_1 both immediately before and immediately after the delivery period. Stated in another way, the overflow periods immediately preceding and immediately following 60 the delivery period overlap the terminal portions of the period when the plunger delivery port is in communication with the cylinder delivery port, the actual delivery period being shorter than the period of communication between these 65 two delivery ports. Thus the pump chamber is temporarily placed in simultaneous communication with a delivery passage and an overflow passage just before actual delivery commences and just after it ceases. 70 75

In the position 8e, the edge 46b of the delivery recess passes the upper edge of delivery port d_1 , overflow continuing to take place during the movement from position 8d to position 8e by the continued communication between overflow 75

channel 48g and relief port r_1 . Before channel 48g passes out of communication with port r_1 , channel 48f comes into communication with port r_2 , and during continued movement of the plunger through positions 8f and 8g, overflow continues through both ports r_1 and r_2 . When position 8h is reached, the delivery recess 46 is about to come into communication with the delivery port d_2 because of edge 46a passing the lower edge of this port, and relief channel 48g passes out of communication with relief port r_1 .

Between positions 8h and 8i, the delivery port d_2 is brought into communication with the delivery recess 46, but no injection takes place during this movement because of the continued communication of overflow channel 48f with relief port r_2 after the overflow channel 48g has passed out of communication with relief port r_1 . When position 8i is reached, delivery period No. 2 commences, since at this instant the overflow channel 48f passes out of communication with relief port r_2 and channel 48g is already out of communication with relief port r_1 .

Delivery continues until relief channel 48g comes into communication with relief port r_2 as shown at position 8j, communication between channel 48g and port r_2 continuing until the delivery recess 46 passes out of communication with port d_2 (position 8k) and to the end of the movement of the pump plunger in the direction of its delivery stroke, as shown in position 8l.

It will be noted that in order to secure the desired continuity of overflow between delivery periods the overflow through the two channels 48f and 48g overlaps, resulting at certain periods in simultaneous overflow through both of these channels.

It will be evident from the above that with a larger number of delivery ports and overflow ports arranged in the manner shown in Figs. 6 and 7, the sequence of delivery periods and intervening overflow periods will take place as in the manner just described, the number of delivery periods corresponding to the number of longitudinally spaced delivery ports provided in the pump cylinder.

In the embodiment just described the delivery ports are located in a zone in the pump barrel nearer to the pump chamber end of the barrel than is the zone in which are located the relief ports. It is, however, immaterial which group of ports is nearer the pump chamber end of the barrel and the reverse of the arrangement shown in Figs. 1 to 8 has been indicated in Fig. 9, in which the relief ports r_1 and r_2 are located in a zone nearer to the pump chamber while the delivery ports d_1 and d_2 are located in a zone further from the pump chamber. Obviously, if the positions of the groups of cylinder ports are reversed, the positions of the delivery and overflow recesses in the pump plunger must also be reversed as indicated in Fig. 9. For purposes of illustration the pump plunger in Fig. 9 has been shown in two positions, b and c, corresponding to the positions b and c of Fig. 8 and illustrating the approach to and commencement of the first delivery period.

It will be apparent that any cylinder delivery port may be at any place on a given circumference lying in a plane normal to the axis of the cylinder bore without affecting the timing of delivery through the port. In some instances it may be desirable to provide for simultaneous delivery to two or more outlets, and as will be appreciated from Fig. 10, this may readily be ac-

complished by placing one or more additional delivery ports, such as d' and d'' , in the same location longitudinally of the cylinder bore as delivery ports d_1 and d_2 , respectively, so that simultaneous delivery may be made through a plurality of delivery ports during each delivery period rather than through a single port.

Referring again to Fig. 7, and having in mind the sequence of operations during the delivery stroke explained in connection with Fig. 8, it will be evident that for any delivery period, as for example the delivery period through port d_1 , the commencement of the delivery period is determined by the control edge 48b closing relief port r_1 and the end of the delivery period is determined by the control edge 48d opening this relief port. With the plunger in the position of rotation shown in Fig. 7, the distance between these control edges is maximum and consequently with the plunger in this position, these edges determine the maximum period of delivery. Further, as long as the plunger is in any position of rotation where these parallel edges are controlling, the length of the delivery period will be constant and the relation of the beginning and end of the delivery period will not vary with respect to the positions of rotation of the cam shaft of the pump. If, however, the plunger is rotated to bring the control edge 48c to a position where it passes port r_1 , as shown in Fig. 11, it will be evident that the delivery period will be shortened because of edge 48c closing port r_1 only after the plunger has travelled farther on its delivery stroke than the position corresponding to the closing position determined by edge 48b, while the position of the plunger at which the relief port is opened by edge 48d remains unaltered. Stated in terms of fuel injection to an engine, this arrangement operates upon adjustment for part load to commence injection at a later time in the cycle of operation of the pump, and consequently at a later time in the cycle of engine operation, while maintaining the end of the injection period constant with respect to the cycle of pump operation.

For some types of engines it may be desirable to maintain the commencement of injection constant with respect to the engine cycle insofar as adjustment of the pump for variations in load is concerned. In order to accomplish this, the arrangement of the control edges may be as shown in Fig. 12, in which the edge 48c for part load control is inclined oppositely as compared with Fig. 11. With this arrangement, the control edge 48b closes port r_1 with the pump cam in the same position of rotation regardless of load adjustment of the plunger. At part load adjustment, however, as shown in Fig. 12, the inclined edge portion opens the relief port earlier in the delivery stroke than would be the case for full load adjustment, in which latter case edge 48d would control the opening of the overflow.

In Fig. 13, still another arrangement of part load control edge is illustrated, which operates to retard the time of closing of the relief port with respect to the pump cycle when part load adjustment is effected, and to advance the time of opening of the relief port with respect to the pump cycle when in this position of adjustment. The arrangement in Fig. 13 in effect combines the arrangement shown in Figs. 11 and 12. From the foregoing it will be evident that in a pump embodying the present invention, substantially any timing variation of part load injection with respect to the operation of the engine to which fuel

is being supplied by the pump may be effected by suitable contouring of the part load control edge.

When the pump is to be used to supply fuel for injection to an engine, the delivery stroke of the plunger is advantageously made in a series of steps, each step including a period of acceleration, a period of constant velocity, and a period of deceleration, and the several steps, one for each injection, being separated by intervening periods 10 when the pump plunger is motionless or substantially motionless.

A curve illustrative of this type of plunger action is shown in Fig. 14, and in Fig. 15 there is illustrated a cam for effecting this type of motion.

Referring to Fig. 14, the ordinates of the diagram represent pump stroke while the abscissae represent cam rotation in degrees. As indicated on the figure, the scale of ordinates to abscissae is approximately three to one and the curve is 20 for a cam of the kind suitable for a pump having four delivery periods per delivery stroke of the plunger. On the curve illustrated, the four delivery periods occur along the portions A, B, C, and D of the curve while the suction stroke is 25 represented by the dotted line portion E of the curve. The delivery periods are effected respectively by the rising portions A, B, C, and D of the cam, these portions being separated by portions I, II and III of constant radius which provide for 30 the intervals of no plunger movement between the several injection periods. While portions I, II, and III are most advantageously of constant radius, they are not necessarily so. The portion 35 E of the cam profile provides for the suction stroke.

It will be evident that the profile of the cam may be varied to give a curve different in form from that just described, but the curve illustrated has been found to be advantageous for securing 40 good injection characteristics.

As will be observed from Figs. 14 and 15 the portion E of the profile of a cam suitable for effecting a series of delivery periods for each delivery stroke, must be relatively steep, and thus 45 this results in a high speed suction stroke as well as a suction stroke of greater length than would be required for a plunger effecting but one delivery period. For this reason the arrangement of the pump suction passage of the pump in line 50 with the cylinder bore, to provide for flow of liquid into the pump chamber without abrupt change in direction, is highly advantageous.

It has been found desirable, in order to insure 55 good delivery characteristics, to provide a certain counterpressure or resistance to the overflow from the several relief ports. This may be accomplished in different ways as is illustrated in Figs. 1, 16, and 17. As shown in Fig. 1, a spring 60 loaded valve 18 opening in the direction of overflow is provided to maintain a predetermined pressure load on the liquid overflowing through the passage 34.

In the arrangement shown in Fig. 16, the overflow passage 34 has inserted therein a choke plug 80, the diameter of the orifice of which will of course determine the extent of the counterpressure developed by overflow. In Fig. 17 the overflow passage is restricted by means of an adjustable plug 82, by means of which the value of the 70 resistance to overflow may be varied as desired.

In the arrangements shown in Figs. 16 and 17, the overflow is returned directly to the suction line 30 and when such direct return of the overflow to the suction line is effected, the return line 75 is advantageously provided as shown in these fig-

ures with an air or vapor collecting pocket 84 located at a high point in the return line and closed by a removable member such as plug 86 which may from time to time be adjusted or removed to vent any air or incondensable gas that may have collected in the chamber. Obviously, the spring loaded ball valve construction shown in Fig. 1 may be embodied in a direct overflow return passage of the kind shown in Figs. 16 and 17 or the forms of choke shown in the latter figures may be incorporated in an independent overflow line of the kind illustrated in Fig. 1. Also, it will be evident that any individual relief passage may be restricted to provide the desired counter-pressure acting on the overflow. 15

Referring now to Figs. 18 to 21, another form of pump embodying the invention is shown, which differs from the construction shown in Fig. 1 only with respect to that portion of the pump illustrated in Fig. 18. This embodiment differs principally from that shown in Fig. 1 by the fact that the delivery and relief ports are not disposed in groups located in two longitudinally separate zones in the pump barrel, but are located in the same zone, and different portions of one plunger 20 recess provide both the plunger delivery port and the plunger overflow ports, avoiding the necessity for two longitudinally separated recesses as in the plunger shown in Fig. 1. One principal advantage of the pump shown in Fig. 18 is that the 30 length of the pump barrel and plunger can be made substantially shorter than in the form shown in Fig. 1.

In the present arrangement, passages 34a, 34b, 34c, and 34d, which terminate at their inner ends 35 respectively in the relief ports r_1 to r_4 , are bored directly through from the opposite side of the pump barrel 20a and communicate with an annular relief passage 34e which in turn communicates with the passage 34. The annular passage 40 34e is provided between the exterior of the pump barrel and the wall of a recess 88 formed in the head portion 16a of the pump casing, the pump barrel being held in position axially by means of a nipple 22a threaded into the recess in the head, 45 and suitably packed against leakage of overflow liquid by packing 90. The barrel is centered by one or more flanges such as the one indicated 20b and is restrained against turning movement by means of locating pins the recesses for which 50 are shown at 24a in Fig. 20.

In this embodiment the several cylinder delivery ports are at the same height in the pump barrel as the corresponding cylinder relief ports and as will be observed from Fig. 18, the bores 55 34b and 34c for relief ports r_2 and r_3 are carried through to the opposite side of the bore to provide the corresponding delivery ports d_2 and d_3 which in turn communicate with the delivery passages 38 and 40. Ports d_2 and d_3 thus lie in the 60 same axial plane as the relief ports. Ports d_1 and d_4 , as will be seen more clearly from Fig. 19, lie in a plane at right angles to the plane of ports d_2 and d_3 . Ports d_1 and d_4 and the transverse 65 passages connecting them with their respective outlet passages 36 and 42 are advantageously formed by continuations of auxiliary bores 92 and 94 which provide openings through the barrel directly opposite and in line with these ports. The 70 auxiliary bores 92 and 94 may be closed by plugs in the same manner that the auxiliary bores, the continuations of which form portions of the overflow and delivery passages of Fig. 1, are closed by plugs 96, but as will hereinafter appear, the bores

92 and 94 may be left open without detriment to operation of the pump.

As will be more clearly apparent from Figs. 20 and 21, the delivery passages 36 and 42 lie close together on the same radial line where they emerge from the top of the barrel and passages 38 and 40 lie close together on a second radial line, at right angles to the first line, where they emerge from the top of the barrel.

10 In order to symmetrically locate the pump outlets and to provide room for the several discharge valves, the head portion of the pump casing is advantageously arranged in the same manner as shown in Fig. 3 and the portions of the outlet 15 passages in the head are brought into communication with the portions in the barrel by means of two channels 40b and 42b which respectively provide communication between the portions of channels 40 and 42 in the head and in the barrel 20 which would otherwise be displaced from each other by 90°.

Turning now to Fig. 22, the operation of the pump on its discharge stroke is illustrated in much the same manner as the operation of the 25 pump of Fig. 1 is illustrated in Fig. 8.

As in Fig. 8 the diagram, for simplicity, shows only two rather than four cylinder delivery ports, and corresponding relief ports. The recess in the pump plunger in the present embodiment is 30 shaped to provide control edges similar in nature and function to the control edges shown in Fig. 7 and need not again be described in detail. In this instance, however, the portion of the recess in line with the cylinder delivery ports d_1 — d_4 35 provides the plunger delivery port.

In position 22a the recess 48 is in communication with the delivery port d_1 and is also in communication with the relief port r_1 by way of the passage 48f. Upward movement of the plunger 40 does not result in commencement of delivery until position 22b is reached, in which position passage 48f passes out of communication with port r_1 . Delivery continues after position 22b is passed until position 22c is reached, when delivery is terminated by passage 48g coming into 45 registration with port r_1 . As the plunger advances from position 22c through positions 22d, 22e, and 22f, passage 48g passes port r_1 , through which overflow occurs and during this period 50 passage 48f comes into communication with relief port r_2 . By the time position 22g is reached, the recess 48 has passed out of communication with delivery port d_1 and is in communication with delivery port d_2 , but delivery through the 55 latter port does not commence until the plunger has reached the position 22h in which position the channel 48f passes out of communication with relief port r_2 . Passage 48g has passed out of communication with relief port r_1 prior to this 60 time, when the plunger is in position 22g. The second delivery period occurs during movement of the plunger from position 22h to position 22i. When the latter position is reached, channel 48g 65 comes into communication with port r_2 to terminate injection. During the remainder of the plunger stroke, to position 22j, the overflow necessary to permit this continued movement is effected by the continued registration of passage 48g with port r_2 . As in the form described in 70 connection with Fig. 8, it will be apparent that the action just described may be continued for additional cylinder ports placed above those shown in Fig. 22.

In the diagram just described, the plunger is adjusted rotationally for full load operation. For

effecting part load operation, the plunger is turned in the same manner as has previously been described in connection with the pump shown in Fig. 1 and the desired timing of part load delivery may be effected in the present embodiment, as in the previously described embodiment, by suitably shaping the part load control edge 48c in any desired way.

It will be remembered that in connection with the construction illustrated in Fig. 19, it was 10 pointed out that the auxiliary bores 92 and 94 for forming the delivery ports d_1 and d_4 might be left open without detriment to operation of the pump. This will be more clearly apparent from a consideration of Fig. 23 showing the ported 15 portion of the pump barrel developed together with the control recess and edge portion of the pump plunger.

As will be seen from this figure, which has been shown with the plunger adjusted for part load 20 operation after having covered port r_1 and the port formed by the bore 92, the control edge 48b covered bore 92 before edge 48c covered relief port r_1 to start delivery through port d_1 . From the figure it will further be apparent that bore 25 92, which would if open act as a relief channel, will not be opened on further movement of the pump plunger before the relief port r_1 is opened, since edge 48d will pass both of these ports at the same time. If the plunger is turned to full load 30 position, that is, moved to the left in Fig. 23 so that the edge 48b is in line with the line of relief ports, it will be evident that this edge will close port 92 as soon or sooner than the relief port r_1 . Stated in another way, the bore 92 will, 35 in all positions of adjustment of the pump plunger, be covered for a period as long or longer than the period when relief port r_1 is covered, so that bore 92 can never have any effect on or in any way interfere with the timing of the delivery 40 period through port d_1 , regardless of the position of adjustment of the plunger with respect to load. Likewise, port 94 can in no way affect the delivery period through port d_4 , which is controlled by the covering and uncovering of the relief port r_4 . 45

With the passages in the pump barrel disposed as above described, it will be apparent that all of the transverse passages for both delivery and overflow may very easily and readily be made by drilling operations which result in the formation 50 of no bores which must subsequently be plugged in order to provide an operative barrel structure. This results in cheap production of cylinder barrels by a minimum of simple drilling operations and aids in one of the objects of the invention 55 which is to produce a satisfactory pump for the purpose intended which may be manufactured at substantially lower costs than pumps heretofore available.

In Fig. 24 there is shown another form of tappet 60 construction which for purposes of illustration has been applied to a pump of the general type shown in Fig. 18 in which the relief and delivery ports are located in the same zone along the length of the barrel. It is of course equally applicable to the type of pump shown in Fig. 1. In this embodiment, the barrel 20b is clamped to the head portion 16b of the pump casing by means of a threaded collar 22b. In the present arrangement, the means for turning the plunger are 65 located above rather than around the tappet structure as in the form shown in Fig. 1 and this means comprises a ring member 68a seated in a suitable bore in the casing portion 10b and having teeth meshing with the load control rack 70 75

70a. The ring 68a is held against longitudinal displacement by a bearing ring 97 which is in turn maintained in position by a snap ring 98 seating in a suitable circular recess in the casing. 5 The tappet 56a is extended at its upper end to form only a shallow cup-like recess for the reception of the plunger head 26a which is held in position by the retaining washer 64a. The tappet is restrained against turning by any suitable 10 means such for example as a locating pin working in a vertical slot in the tappet, or by a lower skirt embracing the sides of the cam, and turning movement is imparted to the plunger by means of the pin 72a fixed at one end in the foot of the 15 plunger and at its other end sliding in slot 74a in ring 68a. Pin 72a passes through an arcuate slot 76a in the tappet in the same manner as in the construction shown in Figs. 1 and 2.

The tappet and plunger are in this instance 20 loaded by means of two heavy helical springs 66 and 66a concentrically arranged between the retaining washer and shouldered portions of the barrel structure. The use of the additional and comparatively large diameter spring 66a is 25 made possible in the present instance because of the fact that the turning means for the plunger is located above rather than around the tappet so that the springs do not have to extend downwardly into the tappet and consequently have 30 available a space of larger diameter than would be the case with the construction shown in Fig. 1 and with a tappet of equal cross-sectional dimensions. Thus, in the form shown in the present figure, a more powerful spring loading can be 35 obtained without having to enlarge this portion of the pump structure.

From the foregoing description it will be evident that in accordance with the present invention a single barreled pump structure can be provided which is relatively cheap to manufacture 40 as compared with multiple plunger pumps and which will at the same time be capable of supplying fuel accurately and in an accurately adjusted quantity to a plurality of separate outlets. 45 Because of the fact that control of the timing of the beginning and ending of each delivery period is effected by a single plunger cooperating with definitely positioned ports, the possibility of variation between the quantities delivered to any two 50 different outlets is substantially eliminated, regardless of the position of adjustment of the plunger with respect to load and also regardless of wear on the pump. If the pump cylinder and barrel wears, the tendency of such wear is to 55 affect all deliveries to the same extent, which is not true of multiple cylinder pumps where wear of unequal magnitude frequently occurs as between different pump plungers and cylinders. Furthermore, since one pump plunger and cylinder 60 assembly serve to effect a multiplicity of deliveries, the manufacture of each pump and cylinder assembly is facilitated because of the fact that the exactness of the matching of the dimensions of cylinder bore and plunger diameter, required 65 for the different pump units of a multiple pump, is not required.

In Figures 25 to 36, inclusive, further different forms of plunger and barrel construction are illustrated, which provide for regulation of the delivery of the fuel from the pump chamber to the delivery conduits in various different manners from that which has been described. In order to illustrate these different forms of pump plunger and barrel arrangements, diagrams similar to 75 those of Figs. 8 to 10, 22 and 23 have been em-

ployed, since the remainder of the pump construction may be the same as shown in Figs. 1, 18, or 24. For the sake of simplicity, only so much will be described in detail with reference to the additional figures as differs from the structures 5 heretofore described.

The arrangement shown in Fig. 25 differs from the previously described embodiments in the location and arrangement of the relief or overflow ports in the barrel, with respect to the plunger 10 overflow ports. Referring now to the figure it will be observed that the plunger 26 is of the form illustrated in Fig. 8 in which a separate plunger delivery recess 46 and a plunger overflow recess 48 are provided. In the present instance two delivery ports d_1 , d_2 are shown, and three overflow ports r_1 , r_2 , and r_3 are provided. The plunger has been shown in two positions c and d corresponding to positions c and d of Fig. 8 and illustrating respectively the commencement and termination 20 of a delivery period.

As will be observed from position 25c, the delivery period through port d_1 is about to commence, since the upper control edge 48b of the control projection 48 is just passing out of communication with the overflow port r_1 to terminate overflow by way of the plunger overflow port 48f. In this position, the delivery recess 46 has already moved into communication with port d_1 . As the plunger moves from the position c to the position 30 d , delivery is effected in the manner previously described in connection with Fig. 8 but the delivery period through port d_1 is, in the present instance, terminated when the plunger reaches position d by the control edge 48a of the recess 35 48 passing the lower edge of the relief port r_2 so that overflow takes place due to communication between the plunger overflow port 48f and the overflow port r_2 . This takes place before the plunger overflow port 48g comes into communication with port r_1 .

It will be evident that by similar action, delivery through port d_2 will be commenced by plunger port 48f passing beyond overflow port r_2 and will be terminated by port 48f coming into 45 communication with port r_3 .

As will be seen from the above, this arrangement differs from the arrangement illustrated in Fig. 8 by the fact that commencement and termination of a delivery period is in the present case 50 determined by the action of a single plunger overflow port in conjunction with two cylinder overflow ports, whereas in the arrangement shown in Fig. 8 commencement and termination of a 55 delivery period are determined by the action of two different plunger overflow ports acting in conjunction with the same cylinder overflow port. In some cases the present arrangement has proved useful rather than the arrangement illustrated in 60 Fig. 8.

In the arrangement shown in Fig. 26, the location of cylinder delivery ports and cylinder overflow ports with reference to each other and to the plunger ports is such as to provide a certain 65 degree of precompression of the fuel in the pump chamber before delivery is commenced so that for each delivery period, high pressure delivery from the very instant of commencement of the delivery period may be insured.

Referring now to Fig. 26, the plunger is of the general form shown in Fig. 8 but with the inclination of the part load overflow control edge 48c the same as in Fig. 12. The arrangement further is similar to that shown in Fig. 8 in that 75

the commencement and ending of the delivery periods is effected by plunger ports **48f** and **48g** cooperating with the same overflow port rather than by the arrangement shown in Fig. 25. In Fig. 26 positions **c** and **d** have also been shown corresponding, in so far as termination and ending of overflow are concerned, to positions **c** and **d** of Fig. 8. As will be observed from position **26c**, the plunger overflow port **48f** has just passed out of communication with the relief port **r₁** so that the liquid is at this point trapped in the pump chamber **28**. In the present arrangement it will be noted, however, that the plunger delivery port **46** is not yet in communication with the delivery port **d₁** and consequently compression of the trapped liquid is effected by movement of the plunger from position **c** to position **c'**. In the latter position the upper edge **46a** of the plunger delivery port passes the lower edge of port **d₁** to commence the delivery period, and delivery continues through port **d₁** until overflow is again established by registry of plunger port **48g** with overflow port **r₁**.

In similar manner, precompression for the delivery period through port **d₂** is effected by port **48f** passing out of communication with port **r₂** before the plunger delivery port **46** comes into communication with port **d₂**.

In the embodiment illustrated in Fig. 26, the amount of precompression is constant regardless of the rotational position of the plunger for load adjustment. Variation of the degree of precompression with variations in load adjustment may, however, be readily accomplished as illustrated in Figs. 27 and 28.

In the form shown in Fig. 27 the upper and lower control edges **46a** and **46b** respectively of the plunger delivery recess **46** are in planes normal to the axis of reciprocation of the plunger **26**, as in the forms previously described, and consequently communication between the plunger overflow port and any given delivery port will be established and cut off in the same stroke positions of the plunger regardless of its position of rotation.

Unlike the previous embodiments, however, the present form provides inclined edges **48a**, **48b**, **48d**, and **48e** so that the channels providing the plunger overflow ports **48f** and **48g** are inclined. With these ports thus inclined it will be evident that any given overflow period will be commenced and terminated in different stroke positions of the plunger for different positions of rotational adjustment thereof. In the figure, the plunger is illustrated with the overflow port **48f** just passing out of communication with the overflow port **r₂** to start precompression prior to registration of port **46** with port **d₂**. It will be seen from the figure that if the plunger is turned to reduce the quantity delivered, that is, so that the control edge **48c** moves to the left from the position shown in the figure, the plunger port **48f** will pass out of communication with the overflow port **r₂** in a lower stroke position of the plunger than the position shown in the drawing. This evidently will result in a higher degree of precompression of the fuel before delivery through the port **d₂** can take place since the pump plunger must travel a greater distance during the interim between the cut-off of overflow and the registration of the delivery ports.

Thus it will be seen that with this arrangement, the degree of precompression increases with adjustment for decrease in load and decreases with adjustment for increase in load.

Variation in the degree of precompression for different load values may also be accomplished as shown in Fig. 28 in which figure the overflow control edges **48a**, **48b**, **48d**, and **48e** are in planes normal to the axis of reciprocation of the plunger so that the times of beginning and ending of the overflow periods remain constant with respect to the stroke position of the plunger regardless of the rotational position of adjustment of the latter. In the present instance control edges **46a**, **46b**, and **46d** of the delivery port **46** are inclined, and in order to illustrate the different ways in which the relation between degree of precompression with respect to load may be varied, the edges of the delivery port have in this form been illustrated as inclined in such manner as to produce increase in the value of precompression upon adjustment to increase the load, which is the reverse of the variation obtained with the form shown in Fig. 27. In Fig. 28 the plunger is again shown with the overflow through port **r₂** just being terminated to start the precompression period, the position of adjustment of the plunger being for full load. If now the plunger is turned to bring the control edge **48c** into play, it will be evident that a higher portion of the control edge **46a** will be in axial alignment with the delivery port **d₂** and consequently less plunger movement will be required after overflow ceases in order to bring the delivery port **46** into communication with the cylinder port **d₂**. This obviously will result in less precompression.

It will be evident from the embodiments shown in Figs. 27 and 28 that increase in the degree of precompression with either increase in load or decrease in load may be obtained as desired by proper sloping, in either case, of the control edges of either the plunger delivery port or the plunger overflow ports, or both. In the forms illustrated in Figs. 27 and 28, the shape of the control projection **48** is such as to provide for constant commencement and variable termination of injection with respect to the pump cycle in the manner previously described in connection with Fig. 12, but this obviously may be varied.

The character of overflow control effected by means of the island-like control projection **48**, described in the previously discussed embodiments, can also as readily be obtained by means of a recess in the pump plunger as illustrated by the embodiment shown in Fig. 29. In this embodiment the plunger is provided with an overflow recess **48''** and an inclined control edge **48c''** and a lower control edge **48e''**. These edges between them provide an overflow channel **48g''**. The positions of the plunger shown at **c** and **d** of Fig. 25 and illustrate the commencement and termination of an injection period. In position **c** the plunger overflow port is just passing out of communication with overflow port **r₁** to start the delivery period through port **d₁**. This delivery period is terminated when position **d** is reached, in which position port **48g''** comes into communication with the overflow port **r₂**.

In the embodiments illustrated in Figs. 30 to 34, the various features illustrated in Figs. 25 to 29 are shown applied to pumps having plungers of the type shown in Fig. 18, which have but one recess, the general action of which pumps has been described in detail in connection with Figures 18 and 22.

Fig. 30 illustrates the action with this type of plunger when a single plunger overflow port, acting in conjunction with two cylinder overflow

ports, determines the commencement and ending of a delivery period. Position *b* of Fig. 30 shows the plunger in the position where delivery through port *d*₁ is commencing due to port *48f* passing out of communication with port *r*₁, and position *c* illustrates the termination of this delivery period which is caused by port *48f* coming into communication with port *r*₂.

Fig. 31 illustrates a variation in which a single plunger overflow port *48f* is provided rather than two spaced ports *48f* and *48g* as in the previously described embodiment. In position *b* the port *48f* has just passed out of communication with overflow port *r*₁ to commence delivery through port *d*₁, this delivery period being terminated by port *48f* registering with port *r*₂, as shown in position *c*. By the time port *48f* has closed port *r*₂ by passing out of communication with this port as illustrated by position *d*, the plunger port is in communication with the delivery port *d*₂ and the second delivery period commences, continuing until the position *e* is reached when port *48f* comes into communication with overflow port *r*₃. It will be evident that turning the plunger to bring the inclined control edge *48c* into action will vary the duration of the delivery periods in the same general manner previously described.

Fig. 32 shows a construction producing action corresponding to that produced by the form shown in Fig. 29. In Fig. 32, position *b* again shows delivery commencing through port *d*₁ due to port *48f* passing out of communication with port *r*₁, and position *c* shows the ending of the delivery period, caused by port *48f* coming into communication with port *r*₂. The action taking place in Fig. 32 as compared with that taking place in Fig. 31 is different in that in Fig. 32 termination of the delivery period is varied with respect to the pump cycle with different load adjustments of the plunger whereas in Fig. 31 the commencement of the delivery period is varied with respect to the pump cycle as the position of the pump plunger is adjusted for different loads.

In the embodiment illustrated in Figs. 33 and 34, an arrangement is shown for producing pre-compression with a plunger having a single recess and functioning similarly to the arrangement illustrated in Fig. 26. Fig. 33 shows the plunger and barrel in diagrammatic section while Fig. 34 shows the surfaces developed into a plane view. In this arrangement the bottom edge *48e* of the plunger recess *48* is in a plane normal to the axis of reciprocation of the plunger while the upper edge *48a* is provided with an offset portion *48a'* into which the control projection *48'* extends, so that the plunger overflow port *48f* is at a different level from that of the delivery port provided by the main portion of the recess *48*. As will be evident from Fig. 33, the control port *48f* passes out of communication with the overflow port *r*₁ before the edge *48a* reaches the delivery port *d*₁, thus providing for a period of pre-compression before the latter port is uncovered. Evidently the same action will take place on the next delivery period when the control projection *48'* will cover the port *r*₂ before the edge *48a* uncovers the delivery port *d*₂.

Variation of precompression for different load adjustments of the pump may also readily be accomplished with this general arrangement as illustrated by the embodiment shown in Figs. 35 and 36. This arrangement is the same as described in connection with Figs. 33 and 34 except that the edges *48a'* and *48b'* are inclined to pro-

vide between them an inclined overflow port passage *48f'*. As will be clearly evident from Fig. 6, rotational movement of the plunger will operate to vary the amount of plunger travel required between the position when an overflow port is covered by the projection *48'* and the position when the next cylinder delivery port is opened.

While in Figs. 35 and 36 the slope of the port *48f'* has been shown such that a greater degree of precompression is effected as adjustment is made for lower load, it will be obvious that the inclination of this port may be made in the opposite direction to produce the opposite relationship between the degree of precompression and value of load adjustment.

In all of the embodiments hereinbefore described, the several overflow ports have all been illustrated as being in the same axially extending plane, and cooperating with a plunger which in any given position of load adjustment travels axially without any turning movement. This arrangement is to be preferred but it will be apparent that the line of overflow ports might be arranged otherwise, for example, spirally and in cooperation with a plunger to which a corresponding spiral motion is imparted by means of an inclined guide slot in the plunger adjusting ring.

Also, while the preferred form of ports has been described and illustrated, in which the cylinder delivery ports are circular and the plunger delivery ports are elongated, it will be evident that the same function is readily obtainable by utilizing circular plunger delivery ports and elongated cylinder delivery ports.

Several modifications hereinbefore described clearly illustrate the fact that the invention may be carried out in many different specific ways which are capable of producing different delivery characteristics. It is to be noted, however, that it is characteristic of all modifications that pump overflow permits advancement of the pump plunger on its delivery stroke between spaced delivery periods. This permits separate injections of fuel to different cylinders of an engine to be made by the pump where the number of engine cylinders and the timing of the injection periods for the engine are such that time intervals must elapse between the termination of one injection period and the commencement of injection to the cylinder next to be supplied with fuel.

While for the purposes of this specification the pump structures embodying the invention have been described principally in connection with use as fuel injection pumps for engines, it will be apparent that the pump is applicable to other uses as for example as an oil pump for supplying lubricating systems and the like.

It will be apparent that many changes and modifications may be made in the several embodiments hereinbefore described, and that certain features may be employed to the exclusion of others, without departing from the principles of the invention, and the invention is accordingly to be understood as limited in its scope only by the scope of the appended claims when they are construed as broadly as is consistent with the state of the prior art.

The broad generic subject matter herein disclosed forms the claimed subject matter of my co-pending application Serial No. 275,974, filed May 26, 1939, as a continuation-in-part of the present application, the claims of the present application being restricted to structures having multiple cylinder overflow ports.

What is claimed is:

1. A pump including a cylinder having a plurality of delivery ports and a plurality of overflow ports, and a cooperating plunger ported to place delivery ports and overflow ports alternately and successively in communication with the pump chamber during the delivery stroke of the plunger.
2. A pump including a cylinder having a plurality of longitudinally spaced delivery ports and a plurality of longitudinally spaced overflow ports, and a cooperating plunger ported to place the pump chamber in communication successively with different longitudinally spaced delivery ports at different times during the delivery stroke, said plunger being further ported to place the pump chamber in communication successively with different longitudinally spaced overflow ports at different times during the same delivery stroke.
3. A pump including a cylinder having a plurality of longitudinally spaced cylinder delivery ports and a plurality of longitudinally spaced cylinder overflow ports, and a plunger having a circumferentially extending recess intermediate its ends and in communication with the pump chamber, said recess providing a plunger delivery port located to communicate with different cylinder delivery ports in different plunger positions on the discharge stroke and further providing two longitudinally spaced plunger overflow ports located to communicate in sequence with the same cylinder overflow port in different plunger positions on the discharge stroke to determine the duration of the period of delivery through a corresponding cylinder delivery port.
4. A pump including a cylinder having a plurality of longitudinally spaced cylinder delivery ports and a plurality of longitudinally spaced overflow ports located in the same zone longitudinally of the cylinder bore, and a cooperating plunger ported to provide plunger delivery port means located to communicate in different plunger positions on the delivery stroke with different cylinder delivery ports, said plunger further being ported to provide plunger overflow port means located in the same zone longitudinally of the plunger as the plunger delivery port means but peripherally displaced therefrom for communication with different cylinder overflow ports in different plunger positions on the delivery stroke to determine the duration of the different periods of delivery through said cylinder delivery ports, said plunger port means being in communication with the pump chamber.
5. A pump including a cylinder having a plurality of longitudinally spaced cylinder delivery ports located in a first zone in the cylinder bore and a plurality of longitudinally spaced cylinder overflow ports located in a second and longitudinally different zone in the cylinder bore, and a cooperating plunger ported to provide plunger delivery port means located to communicate in different plunger positions on the delivery stroke with different cylinder delivery ports, said plunger further being ported to provide plunger overflow port means longitudinally spaced from the plunger delivery port means and located to communicate in different plunger positions on the discharge stroke with different cylinder overflow ports to determine the duration of the different periods of delivery through said cylinder delivery ports, said plunger port means being in communication with the pump chamber.
6. A pump including a cylinder having a plurality of longitudinally spaced cylinder delivery ports situated in different axial planes and a plurality of cylinder overflow ports longitudinally spaced in line in the cylinder, and a cooperating plunger having a plunger delivery port located to communicate with different ones of said cylinder delivery ports in different positions of the plunger during its delivery stroke, said plunger further having longitudinally spaced plunger overflow ports located to communicate with different ones of said cylinder overflow ports in different positions of the plunger during its delivery stroke to determine the duration of the different periods of delivery through said cylinder delivery ports, all of said plunger ports being in communication with the pump chamber.
7. A pump including a cylinder having a plurality of longitudinally spaced cylinder delivery ports and a plurality of longitudinally spaced cylinder overflow ports, and a cooperating plunger having a plunger delivery port in communication with the pump chamber and located to communicate successively with a plurality of said longitudinally spaced cylinder delivery ports during one delivery stroke of the plunger, and said plunger further having a plurality of longitudinally spaced plunger overflow ports in communication with the pump chamber and located to communicate in succession with said cylinder overflow ports to determine the durations of the different periods of delivery through said cylinder delivery ports.
8. A plunger pump including a cylinder having a plurality of delivery ports and a plurality of overflow ports, and a plunger ported to place delivery and overflow ports in communication with the pump chamber in alternation to provide alternating delivery and overflow periods during the delivery stroke of the plunger, certain of the overflow and delivery ports being temporarily in simultaneous communication with the pump chamber.
9. A plunger pump including a cylinder having a plurality of longitudinally spaced delivery ports communicating with different pump outlets, a plurality of longitudinally spaced overflow ports, and a plunger ported to place the delivery and overflow ports in communication with the pump chamber in predetermined order during the delivery stroke of the plunger to provide alternating delivery and overflow periods during said delivery stroke, said plunger having control edges cooperating with the cylinder overflow ports during the delivery stroke of the plunger to determine the timing and duration of the overflow periods, whereby to determine the timing and duration of the delivery periods.
10. A plunger pump including a cylinder having a plurality of longitudinally spaced delivery ports communicating with different pump outlets and a plurality of longitudinally spaced overflow ports, a plunger ported to place the delivery and overflow ports in communication with the pump chamber in predetermined order during the delivery stroke of the plunger to provide alternating delivery and overflow periods during said delivery stroke, said plunger having control edges cooperating with the cylinder overflow ports during the delivery stroke of the plunger to determine the timing and duration of the overflow periods, whereby to determine the timing and duration of the delivery periods, at least one of said control edges being inclined with respect to the axis of reciprocation of the plunger to vary

the duration of said overflow periods when the plunger is turned to bring different portions of said inclined edge into cooperating relation with the cylinder overflow ports, and control means 5 for adjusting the position of rotation of the plunger with respect to the cylinder.

11. A plunger pump including a plurality of longitudinally spaced cylinder delivery ports and a plurality of longitudinally spaced cylinder overflow ports located respectively at the same levels in the pump cylinder as the delivery ports, a plunger having a circumferentially encircling recess intermediate its ends, a passage providing communication between said recess and the pump 10 chamber, and an island-like control projection extending from said recess to provide plunger overflow ports above and below the projection, said cylinder overflow ports being arranged in line, and plunger actuating means for reciprocating the plunger in a position of rotation such that said control projection follows said line of cylinder overflow ports, whereby to determine delivery periods from the cylinder by determining the timing of the overflow through said cylinder overflow ports. 15

12. A plunger pump including a plurality of longitudinally spaced cylinder delivery ports and a line of longitudinally spaced cylinder overflow ports, a ported plunger having a circumferentially encircling recess intermediate its ends, a passage providing communication between said recess and the pump chamber, an island-like projection of irregular shape extending from said recess to form plunger overflow ports above and below the projection, at least one of said ports being of different axial extent at peripherally different places on the plunger, means for reciprocating the plunger with said projection following the line of cylinder overflow ports, and means for turning the plunger peripherally within a range of movement in which said projection remains in line with said ports to bring different portions of said plunger overflow port of different axial extent into communication with said cylinder overflow ports to vary the duration of the overflow periods. 20

13. A plunger pump having a cylinder and a plurality of overflow ports connected to different pump outlets, a line of longitudinally spaced overflow ports in the cylinder, a plunger ported to cooperate with said overflow ports and with said delivery ports to determine a series of delivery periods from the cylinder to said outlets during the delivery stroke of the plunger, a cam for actuating said plunger, a tappet interposed between the cam and the plunger, a control member mounted for turning movement in the casing adjacent the lower end of the plunger, said member being restrained against axial movement, means 25 connecting said plunger and said member to cause them to turn together, there being a sliding connection between said member and said plunger to permit reciprocation of the plunger relative to said member, said sliding connection guiding the plunger to cause the plunger overflow ports to follow the line of said cylinder overflow ports during the delivery stroke of the plunger. 30

14. A pump including a plunger and a cylinder cooperatively ported to deliver to different pump outlets at different times during the delivery stroke of the plunger and having a line of longi-

tudinally spaced overflow ports arranged in said cylinder in a single axial plane for controlling delivery through the overflow ports, a cam for actuating the plunger on its delivery stroke, a tappet interposed between the cam and the 5 plunger, a turnably mounted member for controlling the position of rotation of the plunger relative to said line of overflow ports, and means including a sliding connection for causing the plunger to turn with said member, said sliding connection being positioned to insure straight axial reciprocation of the plunger without turning movement relative to the axial line of overflow ports in any given position of rotation of said turnably mounted member. 15

15. In a plunger pump, a cylinder having a plurality of delivery ports opening laterally into the bore of the cylinder, each of said ports constituting the inlet of a delivery passage formed in part by a laterally extending bore in the wall of the 20 cylinder, a plurality of cylinder overflow ports opening laterally into the bore of the cylinder and constituting the inlets of overflow passages passing through the wall of the cylinder, at least certain of said laterally extending bores constituting 25 extensions of auxiliary bores extending through the wall of the cylinder opposite the respective delivery ports, and a ported plunger operating in said cylinder, said ports and said bores being so located in the cylinder with respect to each other 30 and to the plunger ports that said auxiliary bores are covered by the plunger whenever said overflow ports are covered. 35

16. A pump including a cylinder having a series of delivery ports axially spaced from each other 35 in the cylinder bore and a series of overflow ports axially spaced from each other in a peripherally different part of the bore from the delivery ports, there being at least one more port in said series of overflow ports than in said series of delivery 40 ports, and a plunger reciprocably mounted in said bore having a delivery port located to register with the series of cylinder delivery ports in sequence during one discharge stroke and having an overflow port located to register with the series of cylinder overflow ports in sequence during 45 the same discharge stroke, the several ports being located to bring the cooperating overflow ports and the cooperating delivery ports into communication in alternation during said stroke 50 and with overflow ports being the first and the last to communicate during said stroke. 55

17. A pump including a cylinder having a series of delivery ports axially spaced from each other in the cylinder bore and a series of overflow ports 60 axially spaced from each other in a peripherally different part of the bore from the delivery ports, there being the same number of ports in each series, and a plunger reciprocably mounted in said bore having a delivery port located to register with said series of cylinder delivery ports in sequence during one discharge stroke and having two axially spaced overflow ports each located to register with said series of overflow ports in sequence during the same discharge stroke, the registration at different times of the different plunger overflow ports with any one cylinder overflow port of the series determining the beginning and the ending of delivery through the corresponding cylinder delivery port. 65
